UNITED STATES PATENT OFFICE.

JAMES C. MEEM, OF BROOKLYN, NEW YORK, ASSIGNOR OF ONE-HALF TO FREDERICK L. CRANFORD, OF BROOKLYN, NEW YORK.

SECTIONAL SHEATHING.

1,282,904.

Specification of Letters Patent.

Patented Oct. 29, 1918.

Application filed April 9, 1917. Serial No. 160,650.

To all whom it may concern:

Be it known that I, JAMES C. MEEM, a citizen of the United States, residing at Brooklyn, in the county of Kings and State 5 of New York, have invented certain new and useful Improvements in Sectional Sheathing, of which the following is a specification.

In making excavations for permanent constructions of various kinds and for other 10 purposes, it is commonly necessary to provide temporary supports for the sides of the excavation, particularly where the excavation is near the foundation of buildings or in loose or sandy soil.

15 The general object of this invention is to provide a method and form of construction of a temporary character for supporting the side walls, which will be economical in cost of material and in cost of erection, while 20 likewise obtaining a construction which will afford maximum strength and occupy comparatively small space, and may if desired be used permanently.

In making excavations heretofore, it has 25 been common to provide heavy wooden planking or metal sheathing adjoining each other and vertically placed; and as the excavation proceeds, these planks are driven downwardly endwise into the soil, the planking being braced by cross stays when necessary. 30 The principal objection to this method is that when the sheathing is driven downwardly, it commonly strikes many points where it is impossible to drive the sheathing, 35 due to stones, and the like, so that it is impossible to force parts of the sheathing along with the rest. This results in retarding the work until the excavation has proceeded far enough to remove the obstructions. 40 This difficulty also is likely to cause the entire sheathing to be loosened and have less strength not only in particular places, but in the construction as a whole. Also where excavations have to be made under the 45 planking, there is no opportunity to afterward fill in back of the planking so as to give a solid support for the soil. Such construction is also expensive in the material used as well as in the amount of labor required.

50 In accordance with my invention, I utilize rolled steel strips of special shape for retaining the soil in place and I place these cross-wise to the direction in which the exca-

vating proceeds. I also provide suitably 55 spaced supporting posts alined in the direction in which the excavating proceeds for retaining the strips in position. My improved method and form of construction will be understood from the following de- 60 scription.

Figure 1 is a vertical cross section of a trench and construction illustrating a preferred embodiment of my invention; Fig. 2 is a section on the line 2—2 of Fig. 1; Fig. 3 65 is a perspective view of a modified form of supporting strip; Fig. 4 is a similar view of another modification, and Fig. 5 is a similar view of my preferred form shown in Figs. 1 and 2. 70

Referring to Figs. 1 and 2 the posts or rangers 6 of wood or other suitable material are first placed in position vertically, and second by bracing at the top in any suitable way, such as by horizontal rangers 7 and 75 cross pieces 8. The lower ends are braced or sunk into the soil sufficiently and hold them in place. These vertical rangers 6 are spaced a suitable distance apart and in planes which are to form the boundaries of 80 the excavation. The location of these posts in their planes may be selected as desired. As the excavating proceeds between the planes of the posts, the soil is removed to a slight degree back of their planes sufficiently 85 to permit the endwise insertion of the strips 9 preferably of cold rolled steel. In the form shown in Figs. 1, 2 and 5, the strips have a rounded central portion 10, straight vertical portions 11, 11' and flanged outer 90 portions 12, 12' extending in opposite directions from the straight portions 11, 11'. It will be seen that the shape of these strips is such that they may be rolled from sheet steel in one rolling operation. These strips 95 are placed with the convex surface of the rounded portions 10 against the back of posts 6 and with the flange 12 uppermost and extending toward the posts and the flange 12' extending away from them. 100

As the excavation proceeds, these strips 6 are placed in position one at a time under the strip immediately above it, one end being inserted back of one post and pushed along until the opposite end of the strip clears the 105 adjoining post and then slid along back of it. Soil is then filled in and tamped back of the strip last positioned through the space

between flanges 12, 12' of adjoining strips, the flange 12 serving as a convenient guide for the filling. As the excavation proceeds these strips are successively inserted, one beneath the other, although in some instances two or more may be inserted at a time. When the soil is such that it cannot be excavated greatly in advance of the sheathing, a pair of posts 6, 6' may be used as shown in Fig. 2, and alternately braced and driven. Thus the posts 6 may be loosened, as by removing its wedges 13 and as the horizontal sheathing strips 9 are placed, the loose posts are driven over them to hold the strips in place. The loose posts are then braced or tightened as by wedges 13, leaving the posts 6' free to be loosened and driven on, and driven or slid downwardly after placing the next strip 9. When the length of the sliding posts has been exceeded, permanent vertical rangers 14 are set in place and braced in the positions previously occupied by the posts 6, 6', or alongside of them, leaving the sliding posts free to be moved downwardly. Where the length of the excavation exceeds the length of the strips, another section of strips are built up and similarly supported, the ends of adjoining strips overlapping and fitting into each other as indicated at 15 in Fig. 2.

It will be seen that the strips are of comparatively light weight, and easily handled and may be conveniently placed in position and also occupy small space requiring little extra excavating. Their shape is also such as to give great strength and rigidity in a direction to resist longitudinally the pressure between vertical rangers, as well as to resist pressure in a vertical direction. Their shape is also such as to be held firmly in position by the filling in back of and between the strips. Where greater longitudinal resistance may be required, it may be gained by increasing the ratio of the depth of the rounded portion 10 to its span. The preferred form shown in Figs. 1, 2 and 5 is especially adapted to permit the filling to be facilitated by tamping filling material through the horizontal space between two adjacent strips. The shape of my improved sheathing is also such as to avoid cutting into the unexcavated soil or unnecessarily loosening or otherwise disturbing such soil. Also their shape is such as to occupy small storage space and small space during transportation, being easily stacked by fitting one within the other.

In Fig. 3 the strip is of a simpler shape, having a central rounded portion 10' and 60 reversely formed flanges 16, 16' at the edges. Fig. 4 illustrates another form of strip having a rounded central portion 10" and flanges 17, 17' lying in the same vertical plane. Various other shape of strips may be

used giving great strength and rigidity in 65 resisting the pressure of the side walls and of a character to be firmly held in place by the soil.

The structure is adapted to be removed in case of necessity when the excavation is 70 filled in, and without disturbing the side walls of the embankment except at the lowermost parts; the strips being successively removed beginning with the lowest ones and removing them gradually just above the bottom of the excavation as the filling in proceeds.

It also is adapted to be used adjacent to structures or to building foundations and the like, where the eventual rotting out of 80 temporary sheathing would do permanent injury.

I claim:

1. The method of excavating and supporting side walls which consists in placing pairs 85 of vertical posts spaced apart at intervals from each other along the line of the side wall as the excavation proceeds, and inserting metal strips back of said posts horizontally, said posts of each pair being driven 90 alternately, said strips having cylindrically convex sides bearing against the posts and being inserted below each other as the excavation proceeds.

2. The method of excavating and supporting side walls which consists in placing vertical posts in pairs spaced apart from each other at intervals along the line of the side wall as the excavation proceeds, successively inserting horizontal strips spaced apart below each other and behind said posts as the excavation proceeds, and alternately loosening and driving said vertical posts as the said strips are inserted and as the excavation proceeds, and tamping filling material 100 behind said strips through the horizontal spaces between said strips.

3. The method of temporarily supporting a side wall when excavating beside it which consists in placing braced vertical posts in 110 pairs at intervals along the line of said wall, slidably engaging horizontal strips below one another behind said posts, as the excavation proceeds, and loosening the bracing for said posts and driving them down alternately as the excavation proceeds.

4. A temporary support for side walls comprising vertical posts spaced apart and along the line of the wall, and horizontal strips of sheet metal one below another and 120 back of said posts, each of said strips having a cylindrically convex surface of longitudinal elements, against said posts.

5. A temporary support for side walls comprising vertical posts spaced apart and 125 along the line of the wall, and horizontal strips of sheet metal one below another and back of said posts, each of said strips hav-

ing a cylindrically convex surface of longitudinal elements against said posts and a flange at the edge of each said strip.

6. A temporary support for side walls comprising vertical posts spaced apart and along the line of the wall, and horizontal strips of sheet metal one below another and back of said posts, each of said strips having a cylindrically convex surface of longitudinal elements against said posts and an outwardly extending flange at the edge of each said strip.

7. A temporary support for side walls comprising vertical posts spaced apart and along the line of the wall, and horizontal strips of sheet metal one below another and back of said posts, each of said strips having a cylindrically convex surface of longitudinal elements against said posts and an upwardly and outwardly extending flange at the top edge of each said strips.

8. A temporary support for side walls comprising vertical posts spaced apart and along the line of the wall, and horizontal strips of sheet metal one below another and back of said posts, each of said strips having

a cylindrically convex surface of longitudinal elements against said posts, an outwardly and upwardly extending flange at the top edge of each said strip, and a downwardly and inwardly extending flange at the lower edge of each said strip.

9. A temporary support for side walls comprising vertical posts spaced apart and along the line of the wall, and horizontal strips of sheet metal one below another and back of said posts, each of said strips having a central cylindrical convex portion of longitudinal elements against said posts, vertically extending portions above and below said central portion, an upwardly and outwardly extending flange at the top, and a downwardly and inwardly extending flange at the bottom.

10. A rolled metal section for sheathing trenches or excavations, said section having a single median convex web and an upwardly and outwardly extending flange at the top and a downwardly and inwardly extending flange at the bottom.

JAMES C. MEEEM.
